HINGE

Norman J. Peters, Fond du Lac, Wis., assignor to
Damrow Brothers Company, Fond du Lac, Wis.,
a corporation of Wisconsin

Application July 8, 1938, Serial No. 218,095

1 Claim. (Cl. 16—153)

The invention relates to doors and more particularly to automatically swinging doors that may be used in conjunction with a conveyor to close an entrance to material carried on said conveyor except when the material is passing through this entrance.

One object of the invention is to provide a self-closing door structure that will swing to closed position in either direction and will be held in engagement with a door stop in its closed position.

A further object of the invention is to provide a self-closing door having a hinge provided with a cam member adjustable to bring the door tightly against its stop when in its closed position.

The invention further consists in the several features hereinafter set forth and more particularly defined by claim at the conclusion hereof.

In the drawing:

Fig. 1 is a front elevation view of a door construction embodying the invention, parts being broken away;

Fig. 2 is a detailed sectional view taken on the line 2—2 of Fig. 1;

Fig. 3 is a detailed sectional view taken on the line 3—3 of Fig. 1;

Fig. 4 is a detailed side elevation view of the upper cam member of a hinge for the door;

Fig. 5 is a front elevation view of the upper cam member;

Fig. 6 is a front elevation view of the lower cam member of a hinge for the door;

Fig. 7 is a detailed sectional view taken on the line 7—7 of Fig. 6;

Fig. 8 is a detailed perspective view of the door stop;

Fig. 9 is a detailed view of the lower portion of the door;

Fig. 10 is a detailed sectional view taken on the line 10—10 of Fig. 9;

Fig. 11 is a view, partly diagrammatic, showing the applicability of the invention to a single door.

Referring to the drawing, the numeral 12 designates generally the jamb or frame of the door including the steel uprights 13 and the cross frame member 14 welded thereto. These uprights 13 are in the general form of angles having channels or grooves 15 formed in the front leg or face, said grooves forming guideways for a panel 16 or door 17 of wood, metal, or other suitable material that may be inserted therein to completely close off the entrance when it is not desired to use the same.

In Figs. 1 to 3, inclusive, a double door form of the invention is shown. Each door 17 is a rela-

tively flat steel plate having notches 18 at one edge and a U-shaped groove 19 along this edge for receiving a hinge rod 20 which is secured in said groove by welding or brazing said rod to said door. The upper end of the rod 20 projects through an opening 21 in a hinge member 22 which is in the form of a metal angle member which may be welded onto a stop member 23. The stop member 23 is in the form of a steel channel member having its upper leg 24 detachably secured to the top jamb member 14 by bolts 25 and its lower leg 26 acting as a stop for the door, said member 23 being reversible to present the edge of the leg 26 to either side of the door, so that said stop may be used with doors opening in either direction. The lower leg 26 of the stop member 23 is cut off at its ends to accommodate the hinge members 22.

The lower end of the rod 20 is formed as a pin 27 with a threaded portion 28 adjacent thereto. The pin 27 fits in a vertically disposed bore 29 of a stationary hinge member 30 bolted or otherwise suitably secured to the jamb member 13. The threaded portion 28 has a hinge member 31 adjustably threaded thereon and adapted to be secured thereto in different positions of adjustment by a lock nut 32.

The hinge members 30 and 31 have cooperative sets of cam surfaces 33 and 34, one set of said surfaces adapted to engage with each other as the door swings from open to closed position, the weight of the door causing an engagement of the upper hinge member 31 against the lower hinge member 30, the cam surfaces 33 and 34 being so designed as to cause the door to be pressed tightly against its stop, the cam member 31 being adjusted so that it is riding on the surface 33 throughout the whole of its movement as will be apparent from Fig. 3. Thus with this arrangement the doors may always be kept tight up against their stop when in closed position.

With this arrangement as an article such as a milk can 35 passes along the roller conveyor 36, it engages the inner portions of the doors 17 and swings them to the open position as shown by the dotted lines in Fig. 2, and then after the can passes by these doors, they swing back automatically, due to their own weight, to a closed position against the stop member 23, it being noted that the stop member is reversible, so that the edge of the leg 26 may be arranged to engage doors that swing inwardly or outwardly. When, as noted above, the conveyor is not in use, the entrance provided by the doors may be shut off by the panel 16 inserted in the grooves 15.

In some instances, a single door structure such as the door 37 indicated in Fig. 11 may be used, this door having a hinge mounting similar to one of the double doors and similarly associated with 5 a stop member similar to the first construction.

I desire it to be understood that this invention is not to be limited to any particular form or arrangement of parts except in so far as such limitations are included in the claim.

What I claim as my invention is:

A door hinge structure comprising a pair of cooperative cam hinge members and a rod, one of said hinge members adapted to be secured to the door jamb and the other of said cam members lengthwise adjustably threaded on said rod, said rod adapted to be fixed to the door.

NORMAN J. PETERS.
